CLAIM

The ornamental design for broach, as shown and described.

DESCRIPTION

FIG. 1 is a front elevation view of broach showing my new design.

FIG. 2 is a right side elevational view;

FIG. 3 is a rear elevational view;

FIG. 4 is a left side elevational view;

FIG. 5 is a top plan view;

FIG. 6 is a bottom plan view;

FIG. 7 is a view taken along line 7—7 of FIG. 1 for clarity;

FIG. 8 is a front elevational view of a broach showing a second embodiment of my new design with insert;

FIG. 9 is a right side elevational view of FIG. 8;

FIG. 10 is a front elevational view of a broach showing a third embodiment of my new design with the bottom portion reversed;

FIG. 11 is a right side elevational view of FIG. 10;

FIG. 12 is a front elevational view of a broach showing a fourth embodiment of my new design with the halves reversed;

FIG. 13 is a right side elevational view of FIG. 12.
